UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM-BOILER ECONOMIZER SYSTEM.

1,393,445.

Specification of Letters Patent. Patented Oct. 11, 1921.

Application filed February 27, 1918. Serial No. 219,389.

To all whom it may concern:

Be it known that I, DAVID S. JACOBUS, a citizen of the United States, residing at Jersey City, in the county of Hudson and State of New Jersey, have invented certain new and useful Improvements in Steam-Boiler Economizer Systems, of which the following is a specification.

The presence of air and gases in boiler feed water is a well-recognized cause of corrosion in both boilers and economizers, and in order to prevent or minimize such corrosion I have in my Patents Nos. 1,219,320 and 1,219,321, granted March 13, 1917, described systems in which the feed water is heated, then conducted from the heating means and the air or other gases allowed to escape therefrom, and the water then fed, preferably by a pump, into the economizer 10 or a part thereof which is under boiler pressure. The apparatus employed for heating the water before passing it to a tank for the elimination of air or gases, may be either the low pressure stage of a plural stage 15 economizer, or a separate apparatus heated independently of the waste gases of the boiler. In my said patent, and in the present application, I have illustrated a form of my invention in which the former method of 20 heating is provided for.

The present invention has been designed more particularly as an improvement upon the system described in my said Patent No. 1,219,321 in which a common tank for the 25 elimination of air or gases receives the water heated in the low pressure stages of the economizers of a plurality of boilers and also for providing a means for regulating the pressure in the low pressure stage of 30 the economizer to prevent steaming under certain conditions of operation. According to the present system instead of conducting the heated water directly to a common tank, I provide an individual or separate tank for 35 each low pressure stage, and a common tank to which the water from the individual tanks is conducted. For regulating the pressure in the low pressure stage of the economizer I provide a relief valve which may be 40 adjusted at the exit of the low pressure stage.

My invention will be understood by reference to the accompanying drawings in which Figure 1 is a diagrammatic view, in side elevation, of a plant in which the economizers are placed in pairs above the boilers, and Fig. 2 a diagrammatic plan view of the arrangement for two boilers. Similar reference numerals indicate similar parts in the two views.

For the purpose of describing my invention, the general arrangement of the boilers and economizers may be substantially the same as shown in United States Patent No. 1,048,739, dated December 31, 1912, that is, the boilers 1 and 2 may be set back to back, as illustrated, although this is not essential. Placed side by side above the boilers are two economizers each comprising a low pressure stage or section 3, and a high pressure stage or section 4 constructed generally as indicated in Fig. 1 of my said Patent No. 1,219,320. The economizers are located in the boiler outlet flues 5 and are so arranged that the high pressure section is subjected to the hottest gases and the low pressure section to the coldest gases and, as shown in Fig. 2, the waste gases from boiler 1 flow through its economizer in an opposite direction to the flow of gases from boiler 2 through its economizer. Fans 6 provide the necessary draft suction and deliver the gases to the stacks 7.

The water from the hot well, or other source enters through pipe 8 and is distributed through branch connections 9, each having a controlling valve, to the low pressure sections 3. The outlets from the low pressure sections are pipes 9' leading to the relief valves 10 and to tanks 11 placed above and in relatively close proximity to the economizers, and open to the atmosphere. The relief valves 10 may be adjusted to maintain any desired pressure above the atmosphere in the outlet pipes 9' leading from the low pressure stages of the economizer, or they may be fully opened in case the temperature of the water in the low pressure stages is at all times well below the boiling point. Thermometers 12 are placed in the pipes 9'. The water overflows 95 100

from the tanks 11 through pipes 13 to a common tank 14 shown as having a series of perforated plates 15 over and through which the water is caused to flow to break it up and to assist in the separation of any remaining air or gases therefrom. In the bottom of the tank 14 is a filter 16, the water after passing through the filter flowing through a pipe 17 to the feed pump 18. By 10 the latter the water is forced through pipe 19, having valved branch connections 20, into the high pressure sections 4 of the economizers against the boiler pressure. From the high pressure sections the water 15 flows through pipes 21 to the steam and water drum 22 of the corresponding boiler. The pipes 8 and 19 are shown as open-ended to indicate that more than two boilers may be included in the plant.

20 The open tanks 11 are preferably placed at a higher level than the lower pressure stages of the economizers and the piping so arranged that the gas or air will not pocket in the pipes. By so doing, the air and gases, 25 and any steam which may be formed, will rise and be carried along in the natural direction of the flow of the water and the air or other gases, or a portion of them, will escape from the water when it enters 30 the tanks 11.

Placing the open tanks 11 at a higher level than the low pressure stages of the economizer has the further advantage in that it insures steaming at the tanks before the 35 water boils in the low pressure stages of the economizers when the plant is operated with the relief valves 10 fully open, and thus will indicate the approach of a temperature which will cause boiling in the low pressure stages 40 before the water does actually boil therein. The appearance of vapor at the tanks 11 by reason of the water being heated to a boiling point in these tanks before it boils in the low pressure stages, is advantageous for the 45 reason that boiling in the low pressure stages might cause some of the water to be drawn in belches therefrom, or might result in thumping or a water hammer in the low pressure stages.

50 The tank 14 may be closed, or it may be vented directly to the atmosphere, or the water therein may be subjected to a pressure below that of the atmosphere by means of a dry vacuum pump 23 connected to the tank 55 by a pipe 24. Pump 23 may be operated to maintain any desired pressure below that of the atmosphere to assist in the disengagement of the air or other gases from the water, and to effect their removal from the 60 tank 14. By the removal of the air and gases from the water, pitting or corrosion of the tubes of the high pressure sections of the economizers will be prevented or minimized.

As the pressure in the low pressure sections 65 is comparatively low, I am enabled to use cast iron in the construction of said sections and thereby obtain the advantage of cast iron because of its less liability to corrosion. As the pressure in the high pressure sections 70 is the same or higher than that of the boiler, I employ wrought iron or steel in their construction, thereby obtaining the advantage of the stronger unit which will be practically free from corrosion by reason of the elimination 75 of the air and gases from the water.

The novelty in the present system is in the use of the individual tanks 11 at the outlet of each low pressure section, such tanks serving as indicators to detect an excess of 80 temperature in the water. For proper operation, the temperatures of the several volumes of water leaving the low pressure economizer sections should be approximately equal, and in normal operation this temperature is below 85 212° F., and under normal conditions of operation the temperature of the water may be adjusted by observing the thermometers 12. If for any reason the temperature of the water leaving any one of the low pressure 90 sections, reaches 212° F., steam will escape from the water in the corresponding tank 11. These tanks are open to the atmosphere and are so placed that the presence of steam can be readily observed. The use of these tanks 95 therefore affords a means for quickly determining whether the amount of water fed to the low pressure sections is unbalanced to an extent which will cause steaming in any one of the sections, and if such steaming 100 occurs, the rate at which the water is fed and the temperature of the water may be adjusted.

Another advantage resulting from the introduction of the tanks 11 is that by providing an open vent to the atmosphere near each low pressure outlet, there is less danger of producing a water hammer in the system by reason of the generation of steam in one or more of the low pressure sections and the mingling of water and steam with colder water from the other low pressure sections. 105

The tanks 11 serve therefore the triple purpose of a means by which a portion of the air or other gases in the water from the low pressure section of the corresponding economizer may be eliminated; the function of a detector by which the formation of steam in any one of the low pressure sections may be readily observed so as to suggest to the operator the necessity of adjusting the amount of water fed to the low pressure sections to balance the temperature of the water; and as a means to avoid or minimize the production of a water hammer either in the low 115 pressure stages or in the piping leading from the low pressure stages to the common tank. 120

Placing the tanks 11 at a higher level than

the low pressure stages of the economizer, combined with the action of the relief valves 10 makes it possible to operate under all conditions in accordance with the above method 5 without steam forming in the low pressure stages of the economizers. The relief valves may be readily adjusted to conform with the conditions which are found to exist in operating the plant and, as already stated, 10 the conditions may be such that the relief valves may be left fully open, or it may be necessary to adjust them to give a pressure of, say 10 lb. per sq. in. or more above the atmosphere. In some cases where space conditions 15 will not permit the tanks 11 to be placed at a higher level than the low pressure stages of the economizers the relief valves 10 may be placed at a higher level than the low pressure economizer stages and the tanks 20 11 at a lower level, the relief valves 10 being set to provide enough pressure to prevent steaming in the low pressure stages. I prefer, however, to set the tanks 11 at a higher level than the low pressure stages to avoid 25 any pocketing of air or gases in the piping leading from the low pressure stages to the tanks 11.

What I claim and desire to secure by Letters Patent of the United States is:—

- 30 1. In combination, a plurality of boilers, a plurality of economizers each having high and low pressure sections, means for maintaining the water in the sections of each economizer at different pressures, individual tanks arranged to permit the escape of air or gas from the water and serving as detectors to indicate the formation of steam, means for conducting the water heated in the low pressure sections to said tanks, a common tank and means for conducting the water from said individual tanks to said common tank, and means for distributing the water from said common tank to the several high pressure sections of the economizers and from the latter to the boilers.
- 35 2. In combination, a plurality of boilers, a plurality of economizers each having high and low pressure sections, means for maintaining the water in the sections of each economizer at different pressures, individual tanks open to the atmosphere and placed at a higher level than the low pressure stages of the economizers, a common tank means for conducting water heated in the low pressure sections to said individual tanks, and from said individual tanks to said common tank, means for distributing the water from said common tank to the several high pressure sections of the economizers and from the latter to the boilers.
- 40 3. In combination, a plurality of boilers, an economizer for each boiler located in the corresponding outlet flue and having high and low pressure sections so arranged that the waste gases first contact with the high pressure sections and then with the low pressure sections, a plurality of tanks open to the atmosphere, means for conducting the water heated in the low pressure sections to said tanks, a common tank connected to said tanks and arranged to permit the escape of air or gases from the water therein, and means for distributing the water from said common tank to the several high pressure sections of the economizers and from the latter to the boilers.
- 45 4. In combination, a plurality of boilers, a plurality of economizers each having high and low pressure sections and each associated with one of the boilers, means for maintaining the water in the sections of each economizer at different pressures, means for conducting the water heated in the low pressure sections to individual tanks arranged to permit the escape of air or gas from the water and serving as detectors to indicate the formation of steam, and means including connections between said individual tanks for distributing the heated water to the several high pressure sections of the economizers and from the latter to the boilers.
- 50 5. In combination, a plurality of boilers, a plurality of economizers each having high and low pressure sections, means for maintaining the water in the sections of each economizer at different pressures, individual tanks arranged to permit the escape of air or gas from the water and serving as detectors to indicate the formation of steam, means for conducting the water heated in the low pressure sections to said tanks, a common tank and means for conducting the water from said individual tanks to said common tank, means for distributing the water from said common tank to the several high pressure sections of the economizers and from the latter to the boilers, and adjustable means to maintain any desired pressure above the atmosphere in each low pressure section.
- 55 6. In combination, a plurality of boilers, a plurality of economizers each having high and low pressure sections, means for maintaining the water in the sections of each economizer at different pressures, individual tanks arranged to permit the escape of air or gas from the water and serving as detectors to indicate the formation of steam, means for conducting the water heated in the low pressure sections to said tanks, a common tank and means for conducting the water from said individual tanks to said common tank, means for distributing the water from said common tank to the several high pressure sections of the economizers and from the latter to the boilers, and a relief valve for each low pressure section.

to maintain any desired pressure above the atmosphere therein.

7. In combination, a plurality of boilers, a plurality of economizers each having high and low pressure sections, means for maintaining the water in the sections of each economizer at different pressures, individual tanks arranged to permit the escape of air or gas from the water and serving as detectors to indicate the formation of steam, means for conducting the water heated in the low pressure sections to said tanks, a common tank and means for conducting the water from said individual tanks to said common tank, and means for distributing the water from said common tank to the several high pressure sections of the economizers and from the latter to the boilers, each of said individual tanks being at a level 20 higher than the low pressure section to which it is connected.

8. In combination, a plurality of boilers, a plurality of economizers each having high and low pressure sections, means for maintaining the water in the sections of each economizer at different pressures, individual tanks arranged to permit the escape of air or gas from the water and serving as detectors to indicate the formation of steam, means for conducting the water heated in the low pressure sections to said tanks, a common tank, means to maintain a pressure below the atmosphere in said common tank, and means for conducting the water from 35 said individual tanks to said common tank, and means for distributing the water from said common tank to the several high pressure sections of the economizers and from the latter to the boilers.

40 9. In combination, a plurality of boilers, a plurality of economizers each having high and low pressure sections, means for maintaining the water in the sections of each economizer at different pressures, individual tanks open to the atmosphere and placed at a higher level than the low pressure stages of the economizers, a common tank, means for conducting water heated in the low pressure sections to said individual tanks, and 45 from said individual tanks to said common tank, means to maintain a pressure below the atmosphere in said common tank, and means for distributing the water from said common tank to the several high pressure sections of the economizers and from the latter to the boilers.

55 10. In combination, a plurality of boilers, a plurality of economizers each having high and low pressure sections, means for maintaining the water in the sections of each economizer at different pressures, a tank, individual connections between said tank and each low pressure section, each of said individual connections having an open vent to

permit the escape of air or gas from the 65 water and serving as a detector to indicate the formation of steam, and means for distributing the water from said tank to the several high pressure sections of the economizers and from the latter to the boilers. 70

11. In combination, a plurality of boilers, a plurality of economizers each having high and low pressure sections, means for maintaining the water in the sections of each economizer at different pressures, a tank arranged to permit the escape of air or gas from the water therein, individual connections between said tank and each low pressure section, each of said individual connections having an open vent to permit the 80 escape of air or gas from the water and serving as a detector to indicate the formation of steam, and means for distributing the water from said tank to the several high pressure sections of the economizers and 85 from the latter to the boilers.

12. In combination, a plurality of boilers, a plurality of economizers each having high and low pressure sections and each associated with one of the boilers, means for 90 maintaining the water in the sections of each economizer at different pressures, individual piping to conduct the water away from each low pressure section to a common point, each set of said piping provided with an open 95 vent to permit the escape of air or gas from the water and serving as a detector to indicate the formation of steam, and means for distributing the heated water from the common point to the several high pressure sections of the economizers and from the latter 100 to the boilers.

13. In combination, a plurality of boilers, a plurality of economizers each having high and low pressure sections, means for maintaining the water in the sections of each economizer at different pressures, a tank, individual connections between said tank and each low pressure section, each of said individual connections having an open vent to 110 permit the escape of air or gas from the water and serving as a detector to indicate the formation of steam, means for distributing the water from said tank to the several high pressure sections of the economizers 115 and from the latter to the boilers, and adjustable means to maintain any desired pressure above the atmosphere in each low pressure section.

14. In combination, a plurality of boilers, a plurality of economizers each having high and low pressure sections, means for maintaining the water in the sections of each economizer at different pressures, a tank, individual connections between each low pressure section and said tank, each of said individual connections having an open vent to 125 permit the escape of air or gas from the

water and serving as a detector to indicate the formation of steam, means to maintain a pressure below the atmosphere in said tank, and means for distributing the water from said tank to the several high pressure sections of the economizers and from the latter to the boilers.

In testimony whereof I have hereunto signed my name in the presence of two subscribing witnesses.

DAVID S. JACOBUS.
